SAFETY CONTROL FOR FUEL BURNERS

Samuel G. Eskin and Charles K. Strobel, Pittsburgh, Pa., assignors to Robertshaw Thermostat Company, Youngwood, Pa., a corporation of Pennsylvania

Application January 20, 1944, Serial No. 518,958

10 Claims. (Cl. 158—117.1)

This invention relates to control systems and, more particularly, to combined safety and ignition and condition controlling means for fuel burners and the like.

As disclosed in our copending application Serial No. 482,592, filed April 10, 1943, a combined safety and condition controlling system may employ flame or heat sensitive devices for controlling operation of an electromagnetic fuel valve which performs the dual function of safety and condition control. Where the flow of fuel to the main burner is controlled by electromagnetic means which is actuated in accordance with the condition of heat sensitive devices, it is important in the interest of quiet operation to prevent the electromagnetic means from being influenced by the variations in thermal conditions until these are stabilized and actuating values established.

This invention contemplates a complete system of the type indicated requiring no extraneous igniting means for the burner and being relatively free from noise during the burner starting period. The invention thus has for an object the bringing of a safety and condition controlling system for fuel burners into operation by the action of the burner igniting means.

Another object of the invention is to insure quiet operation throughout the entire cycle and particularly during the starting period.

Another object of the invention is to assure required timing of the sequence of operations which place the system in operating condition.

Another object of the invention is to cause the fuel supply to be shut off in the event of either power failure or the absence of a flame at the burner.

Another object of the invention is to minimize the effect of inrush current on the ignition means.

Another object of the invention is to render the apparatus substantially uniform as to operating time over a range of operating conditions.

Other objects and advantages will become apparent from the following description taken in connection with the accompanying drawing, wherein

Fig. 1 is a schematic view of a combined safety, ignition and condition controlling apparatus for a fuel burner embodying the invention;

Fig. 2 is a schematic view of a detail in one operating position; and

Fig. 3 is a schematic view of the same detail in another operating position.

Referring more particularly to the drawing, a gaseous fuel burner 10 and an associated pilot burner 12 are shown as being supplied with fuel by a main fuel pipe 14. The fuel supply to both burners is controlled by a main valve 16 in the fuel pipe 14 and which may be manually operated. Interposed in the fuel pipe 14 between the main valve 16 and the burner 10 is an electromagnetic or solenoid gas valve 18 of any known type which may be arranged, as in this instance, to be opened when sufficient energizing current is supplied to the coil thereof and to be closed by gravity when such current is reduced below a certain minimum value. Operation of the main control valve 16 from closed to open position will permit flow of fuel from the pipe 14 to the pilot burner 12, but fuel is not supplied to the main burner 10 unless the solenoid valve 18 is also in open position.

Electric current for the operation of the apparatus is supplied by the line wires 20 connected to the primary of a transformer 22 which may receive commercial current at the primary at a voltage variation from 105 to 125 volts. In this embodiment, the main valve 16 has a main switch combined therewith which is connected to one line wire 20 by wires 24 and 26. Any suitable means may be incorporated in the combined valve and switch structure 16 to close the switch portion when the main valve portion thereof is actuated to open position. The secondary of the transformer 22 will deliver the current from the line wires 20 at voltages varying in accordance with the primary voltage variation above and below an average of six volts.

Connected to one terminal of the transformer secondary by a wire 28 at a junction A is one branch of a parallel mesh consisting of a flame sensitive element 30 and is connected at the other end by a wire 31 to the opposite junction B of the parallel mesh. The element 30 is positioned adjacent the pilot burner 12 exposed to the heat of the flame thereof and will vary appreciably in resistance according to its heated or unheated condition. The element 30 may be in the form of a coil of wire formed from material having normally a relatively low resistance and a positive temperature coefficient of resistance, forming a ballast resistor. It will be apparent, however, that other types of flame sensitive, heat responsive or thermal resistance elements having the required characteristics may be substituted and that it is not essential that the flame of the pilot burner actually impinge on the coil. Junction B is connected by a wire 32 with

junction C of another parallel mesh included in the circuit, the other junction D of this second parallel mesh being connected by wire 34 to the other terminal of the secondary of the transformer 22. One branch of this second parallel mesh consists of a resistance element 36 which will be hereinafter designated as a valve control resistor. This resistor 36 is also preferably in the form of a coil of wire having normally a relatively low resistance and a positive temperature coefficient of resistance forming a ballast resistor, although as will be apparent hereinafter, a constant resistor could be employed. The valve control resistor 36 is not, however, exposed to the heat of any flame but is adapted to become heated upon passage of electric current therethrough and will change its resistance appreciably in accordance with changes of temperature caused by changes in the value of current flowing through it.

The other branch of the second parallel mesh consists of a constant resistance element 38, hereinafter designated as a pick-up resistor for the solenoid valve 18, and a control switch 39 connected in series circuit therewith. The control switch 39 may take the form of a thermostat including a bimetal arm 40 carrying on one end a pair of contacts disposed one on each side thereof and which upon warping of the arm will engage alternately with contacts 42 and 46, designated hereinafter "hot contact" and "cold contact," respectively, and spaced one from the other. The control switch 39 may be placed in the space to be heated by the main burner 10 and the arm 40 be subjected to the temperature variations therein forming a space thermostat of special form. It will be apparent that this space could well be an oven which is adapted to be heated by the main burner 10 when in operation.

The cold contact 46 is preferably carried upon a second bimetal arm 44 which is adapted to warp when heated. The arm 44, however, is primarily responsive to the heating effect of a coil 47 adjacent thereto and having one end connected to contact 46 and the other end to pick-up resistor 38. A limit-stop 48 is interposed between the bimetal arms 40 and 44 in position to be engaged by the arm 40 to restrain movement thereof toward the arm 44 for a purpose which will be apparent hereinafter. The hot contact 42 is connected by a wire 50 with one end of a constant resistance element 52 hereinafter called the shunting resistor for solenoid valve 18, the other end of this resistor 52 being connected by a wire 54 to junction A of the first parallel mesh. Returning to the first parallel mesh, it will be apparent that another branch of this mesh includes a cut-out 58 which is thermally sensitive and may be of the slow-acting, bimetallic snap-switch type. One terminal of the cut-out 58 is connected by a wire 60 to junction A and the other terminal thereof is connected by a wire 56 to one terminal of the solenoid valve 18. The other terminal of the solenoid valve 18 is connected by a wire 58 to the junction B thus placing the flame sensitive element 38 in parallel circuit with the cut-out 58 and solenoid valve 18.

In addition to the shunt established on the solenoid valve 18 by the flame sensitive element 38, this valve is also arranged to be short-circuited for a predetermined period of time. The temporary short-circuit is established by a control relay 59 in the form of mercury switches comprising timing elements 60 and 62 which are initially closed and embody predetermined time-delay pe-

riods before opening upon energization of a common electromagnetic actuator 64 therefor. The timing element 60 has a delayed opening which is preferably considerably longer than that of timing element 62. In this embodiment the time-delay of element 60 is approximately eighteen seconds while the timing element 62 has a delayed opening of approximately six seconds. Variation in the delayed opening periods of timing elements 60 and 62 may be made as apparent hereinafter. It is to be noted, however, that both these timing elements are designed to close instantly although this arrangement is also subject to modification as will be explained hereinafter. Both timing elements 60 and 62 may be operated as stated by the common electromagnetic actuator 64 connected by wire 66 to junction D and by wire 68 to wire 28.

The aforesaid short-circuit is established by the long delay timing element 60 on solenoid valve 18 and may be traced by a common wire 69 connected at one end to wire 53 and at the other end to a wire 70 and a wire 71 connecting one adjacent terminal of each timing element 60 and 62 together while a wire 72 connects the other terminal of the timing element 60 with wire 31.

The short delay timing element 62 is adapted to control the energization of an electrical igniting means 74 for the pilot burner 12, which igniting means may be in the form of a coil of wire adapted to reach incandescence upon passage of current therethrough. Thus, while wire 69 and wire 70 connect one terminal of the timing element 62 to wire 53, the opposite terminal thereof is connected by wire 76 to one end of ignition coil 74, the opposite end of which is connected by wire 78 to wire 34. Preferably, a constant resistance element 80 is included in the wire 78 to act as an adjusting resistor for the ignition coil 74.

In order to bring the system into normal running operation the main valve 16 is manually opened and will permit fuel to flow to the pilot burner 12. Although such manual operation of the main valve 16 will serve to close the main switch incorporated therewith, the solenoid valve 18 is not energized at this time and no fuel can flow to the main burner 10. The closing of the main switch of valve 16 does, however, energize two principal circuits, one being the ignition circuit and the other the solenoid valve circuit. Moreover, the electromagnetic actuator 64 of the timing elements 60 and 62 is also energized and will remain energized as long as the main switch of valve 16 is closed. It may be assumed that the oven or other space to be heated by the main burner 10 is as yet unheated and the control thermostat 39 has its cold contact 46 engaged with related contact on arm 40.

The ignition coil circuit may be traced from the transformer secondary 22 to junction A, wire 53, wire 69, wire 70, short delay timing element 62 wire 76, ignition coil 74, wire 78, including adjusting resistor 80 back to the secondary of the transformer 22. The ignition coil 74 is therefore energized to igniting temperature and, after the pilot burner 12 is ignited thereby, the timing element 62 will be opened and the circuit become de-energized. Thus, at the end of approximately six seconds, which is the time it takes for timing element 62 to undergo its delayed opening, the ignition coil is placed in a deenergized condition which is maintained for the duration of the normal running period of the main burner 10. As previously mentioned, the six-second time-delay may be modified as desired as long as the function of the delay period is retained.

The long delay timing element 60, which preferably does not open until after the expiration of an eighteen-second time-delay period, maintains the short-circuit on the solenoid valve 18 during the initial ignition or starting period. The valve circuit at this time consists of the series arrangement of the transformer secondary 22, the long delay timing element 60 and the second parallel mesh of valve control resistor 36, pick-up resistor 38, bimetal heater coil 47 and the cold contact 46 engaged with the related contact of bimetal arm 40. This circuit may be traced from the transformer secondary 22 to junction A, wire 53, wire 69, wire 71, timing element 60, wire 72, wire 31, wire 32, junction C of the second parallel mesh which includes valve control resistor 36, bimetal arm 40, cold contact 46, heater coil 47, pick-up resistor 38, junction D and from this junction by wire 34 to transformer secondary 22.

The short circuit established by the long delay timing element 60 on the solenoid valve 18 is removed when this timing element opens the circuit of wires 69, 71 and 72 at the expiration of the eighteen-second time-delay period. During this period the heat of the flame of the pilot burner 12 has caused the ballast resistor 30 to become sufficiently heated and its resistance consequently to be increased so that sufficient current is supplied to the coil of the solenoid valve 18 to cause actuation of this valve to open position. It will be observed that the pick-up resistor 38 for the solenoid valve 18 remains connected in parallel circuit with the valve control resistor 36 owing to the cold contact 46 of the control thermostat 39 being engaged with its related contact on arm 40. It will further be observed that although the resistance value of the ballast resistor 30 is insufficient when this resistor is unheated by the pilot burner flame to cause the solenoid valve 18 to be actuated to open position, such resistance undergoes a gradual increase in value as the ballast coil 30 becomes heated. Thus, if the short-circuit established by the timing element 60 on the solenoid valve 18 were dispensed with, the immediate actuation of this valve to open position would not be assured and noisy operation during the gradual heating of the ballast coil 30 might well occur.

It will now be apparent that the long delay timing element 60 serves the joint purpose of insuring that no fuel may flow from the main burner 10 until after ignition of the pilot burner 12 and, in the case of normal ignition, insuring immediate actuation of the solenoid valve 18 to open position at the end of the longer time-delay period. However, as long as the short-circuit is removed by operation of element 60 after the ballast resistor 30 is somewhat heated it is conceivable that a shorter time-delay than eighteen seconds could be used. That is, the ballast resistor 30 need not be heated to the temperature required to cause opening of the solenoid valve 18 before removal of the short-circuit thereon, but positive elimination of chattering of this valve is accomplished by maintaining the short-circuit for such period as will ensure the ballast resistor reaching such temperature.

Operation of the main burner 10 will serve to increase the temperature ambient to the control thermostat 39 causing movement of the bimetal arm 40 thereof toward the hot contact 42. It may be assumed for the purpose of this description that the bimetal arm 40 now moves to a neutral position engaging neither the cold contact 46 nor the hot contact 42. A circuit is then established from the transformer secondary 22, wire 34 to

junction D, valve control resistor 36, junction C, wire 32, junction B, the parallel mesh of solenoid valve 18 with its cut-out 58 and the ballast resistor 30, junction A back to the transformer secondary 22. In this circuit the pick-up resistor 38 and the shunting resistor 52 are disconnected, as will be apparent, and the current through the coil of the solenoid valve 18 is, consequently reduced in value by removal of resistor 38 from parallel relation with the valve control resistor 36. However, when the bimetal arm 40 of control thermostat 39 moves as described from the cold contact 46 to neutral position the current value which flows through the coil of the solenoid valve 18 is not reduced below the minimum value required to hold the valve in its open or operating position, but the circuit constants are adjusted at the lowest line voltage which may be 105 volts at the primary so that the normal steady operating current is slightly above the minimum value. The resistance value of the parallel circuit in this operating condition is thus increased sufficiently by the high resistance value of the flame sensitive element 30 when heated, to permit sufficient current to be supplied to the coil of the solenoid valve 18 to maintain it in the open position.

After the main burner 10 has been operating for some time the bimetal arm 40 may move to the hot contact position due to the thermostat becoming satisfied whereupon a circuit arrangement is established from the transformer secondary 22 and the valve control resistor 36 in series with the three-branch parallel mesh of flame sensitive resistor 30, solenoid valve 18 and cut-out 58, and shunting resistor 52. The resistor 52 is of such resistance value in shunt with the solenoid valve 18 as to cause this valve to return to closed position.

When the thermostat moves from the hot contact 42 back to the neutral position the solenoid valve 18 remains closed until the bimetal arm 40 warps sufficiently to close cold contact 46. In such event the cycle is repeated owing to the flame sensitive element 30 remaining heated by the flame of the pilot burner 12. In case the flame sensitive element 30 becomes open-circuited sufficient current flows through the cut-out 58 to cause it to operate and cause the solenoid valve 18 to close, providing the control thermostat 39 is in either the cold contact position or neutral position. If, however, the control thermostat 39 is in the hot contact position, the solenoid valve 18 is already closed due to the shunting action of the resistor 52.

The foregoing sequence of operation continues during the normal running condition of the burner to control a condition caused by operation of the burner. The operation of the safety device will now be described.

If the flame of the pilot burner 12 becomes extinguished for any reason when the bimetal arm 40 is in the hot contact position, or in the neutral position upon warping from the hot contact position, then the solenoid valve 18 is already closed at the time of flame failure. If, however, the bimetal arm 40 is in the neutral position upon warping from the cold contact position, the solenoid valve 18 is open. The flame sensitive element 30 will cool in the absence of the pilot burner flame and its resistance will decrease causing a corresponding decrease in the current value to the solenoid valve 18 which then closes. Such closing of the solenoid valve occurs in a relatively short time due to the combined action of the ballast resistor 30 and the valve control

resistor 36. As previously described, the current which flows through the coil of the solenoid valve 18 in a neutral position of the thermostat is only slightly above the minimum value required to hold the valve in its open or operating position. Thus, by making the valve control resistor 36 sensitive to current changes, the decrease in voltage drop across the coil of the solenoid valve will be accelerated whenever an increase in resistance of the valve control resistor occurs upon cooling of flame sensitive resistor 30 and consequent increase of current through the valve control resistor 36. The resulting temperature increase in the valve control resistor 36 causes increase in voltage drop across the resistor and a rapid decrease in voltage drop across the coil of the solenoid valve 18.

In order to make the adjustment of the circuit constants less critical and the shut-off times of the solenoid valve comparatively short, the cold contact 46 of the thermostat is mounted on the bimetal arm 44. Thus, upon closure of the cold contact the bimetal arm 44 will warp from the position shown in Fig. 2 to that shown in Fig. 3. Even if the thermostat arm 40 remains in cold contact position, the contacts separate and rejoin several times as the arm 44 heats and cools upon automatic making and breaking of the circuit. Thus, the bimetal arm 44 serves to open the cold contact 46 independently of the controlled temperature when the cold contact remains closed for a given length of time. The normal operation of the system is not affected by this action of the arm 44 as once the solenoid valve is actuated to open position it remains open until the hot contact is made. Due to the provision of the stop 48 the thermostat arm 40 is restrained from following movement of the arm 44 to the left as viewed in Fig. 3 and a separation of the cold contact 46 from arm 40 can occur as soon as the arm 44 becomes heated by passage of current therethrough. Consequently, the separation of the cold contact has the same effect as movement of the arm 40 to neutral position and the valve closing time is generally short.

It will be apparent that current could be conducted directly to the arm 44 in place of utilizing the heater coil 47 and such variation is within the scope of this invention. In case of power failure the solenoid valve is immediately closed and, as the actuator 64 of the mercury switch is deenergized, the timing elements 60 and 62 are instantaneously reset for another time delayed opening. It will be apparent, however, that the long delay timing element 60 need not necessarily have an instantaneous closing action as long as it becomes closed before the short time-delay timing element 62 becomes open. That is, as the closing action of the long delay timing element 60 does not control the closing action of the solenoid valve 18 but only its opening, it is unnecessary that this timing element be closed at any time greatly in excess of the opening of the short delay timing element 62. However, as the delayed opening of this timing element 62 is only six seconds, it is apparent that instantaneous, or practically instantaneous, closing of the timing element 60 is desirable.

When the current supply is resumed after a failure thereof the transformer secondary 22 is again energized and the normal starting and running cycles of the system will be initiated. Should an open circuit occur in the ignition coil 74, then the system may be brought in operation by ignit-

ing the pilot burner 12 with a match and all of the safety features will be retained.

It will be understood that a constant resistor could be used in place of the current sensitive resistor 36 as the valve control. The system would then operate over a narrower range of voltages and the valve closing time would be increased. However, the system would not in such case be quite as sensitive as the preferred form to rapid voltage variations and the advantages of reduced valve closing time and an extension of the primary voltage range over which the system will operate are believed superior. Considerable flexibility of circuit arrangement results as the value of the respective resistances can be varied to suit different operating conditions. The single solenoid valve functions as a condition and safety control in the arrangement described and a complete safety, ignition and condition controlling system has been provided. It will be apparent that various changes may be made in the form and arrangement of parts and in the details of construction herein disclosed within the scope of the appended claims without departing from the spirit of the invention.

We claim:

1. A control system for fuel burners having main and pilot burners comprising in combination, a source of electrical energy, electrically operable means connected to said source for controlling the supply of fuel to the main burner, said means having an initial position preventing fuel supply to the main burner and being actuatable to another position when current of sufficient value is supplied thereto, a resistance element in circuit with said controlling means and being adapted to vary in resistance in response to variations in current values in said circuit, a second resistance element shunting said controlling means and being located to be heated by the pilot burner, said second resistance element being adapted to vary in resistance in response to thermal variations therein caused by the heat of the pilot burner, and switching means having a timing element for short-circuiting said controlling means for a period during which said second resistance element is adapted to become heated, whereby sufficient current for causing actuation of said controlling means is supplied thereto following operation of said switching means to discontinue the said short-circuit.

2. A control system for fuel burners having main and pilot burners comprising in combination, a source of electrical energy, electrically operated means connected to said source for controlling the supply of fuel to the main burner, said means having an initial position preventing fuel supply to the main burner and being actuatable to another position when current of sufficient value is supplied thereto, a resistance element in circuit with said controlling means and being adapted to vary in resistance in response to variations in current values in said circuit, a second resistance element shunting said controlling means and being located to be heated by the pilot burner, said second resistance element being adapted to vary in resistance in response to thermal variations therein caused by the heat of the pilot burner, means operable in conjunction with said resistance elements for decreasing the total resistance to current flow in said circuit while said controlling means is in said initial position, and switching means having a timing element for short-circuiting said controlling means for a period during which said second resistance ele-

ment is adapted to become heated, whereby sufficient current for causing actuation of said controlling means is supplied thereto following operation of said switching means to discontinue the said short-circuit.

3. A control system for fuel burners having main and pilot burners comprising in combination, a source of electrical energy, electrically operable means connected to said source for controlling the supply of fuel to the main burner, said means having an initial position preventing fuel supply to the main burner and being actuatable to another position when current of sufficient value is supplied thereto, a resistance element in circuit with said controlling means and being adapted to vary in resistance in response to variations in current values in said circuit, a second resistance element shunting said controlling means and being located to be heated by the pilot burner, said second resistance element being adapted to vary in resistance in response to thermal variations therein caused by the heat of the pilot burner, a third resistance element shunting the first said resistance and thereby decreasing the total resistance to current flow in said circuit while said controlling means is in said initial position, switching means having a timing element for short-circuiting said controlling means for a period during which said second resistance element is adapted to become heated, whereby sufficient current for causing actuation of said controlling means is supplied thereto following operation of said switching means to discontinue the said short-circuit, and switching means responsive to operation of the main burner for discontinuing the shunt established by said third resistance element and thereby causing only sufficient current to be supplied to said controlling means to maintain it in said other position.

4. A combined ignition and control system for fuel burners having main and pilot burners, comprising a source of electrical energy, electrically operable means connected to said source for controlling fuel supply to the main burner and having an initial position in which said fuel supply is prevented, switching means having a timing element short-circuiting said controlling means and causing it to remain in said initial position for a predetermined period, igniting means for the pilot burner having a separate connection with said source, second switching means having a timing element operable for electrically disconnecting said igniting means after a predetermined period independent of that of the first said timing element, a resistance element in circuit with said controlling means and being adapted to vary in resistance in response to variations in current values in the said circuit thereof, and a second resistance element shunting said controlling means and being capable of increasing substantially in its resistance as its temperature increases, said second resistance element being exposed to the heat of the pilot burner and causing sufficient current to be supplied to said controlling means for operation thereof from said initial position following expiration of the period of the first said timing element.

5. A combined ignition and control system for fuel burners having main and pilot burners, comprising a source of electrical energy, electrically operable means connected to said source for controlling fuel supply to the main burner and having an initial position in which said fuel supply is prevented, switching means having a timing element short-circuiting said controlling means

and causing it to remain in said initial position for a predetermined period, igniting means for the pilot burner having separate connection with said source, second switching means having a timing element for electrically disconnecting said igniting means after a predetermined period less than that of the first said timing element, electromagnetic means common to both said switching means for operating the same simultaneously to initiate said timing periods, a resistance element in series circuit with said controlling means and being capable of increasing substantially in its resistance upon passage of current therethrough, and a second resistance element shunting said controlling means and being capable of increasing substantially in its resistance as its temperature increases, said second resistance element being exposed to the heat of the pilot burner and causing sufficient current to be supplied to said controlling means for operation thereof from said initial position following expiration of the period of the first said timing element.

6. A control system for fuel burners having main and pilot burners comprising in combination, a source of electrical energy, electrically operable means connected to said source for controlling the supply of fuel to the main burner, said means having an initial position preventing fuel supply to the main burner and being actuatable to another position when current of sufficient value is supplied thereto, a resistance element in circuit with said controlling means and being adapted to vary in resistance in response to variations in current values in said circuit, a second resistance element shunting said controlling means and being located to be heated by the pilot burner, said second resistance element being adapted to vary in resistance in response to thermal variations therein caused by the heat of the pilot burner, switching means having a timing element for short-circuiting said controlling means while said second resistance is becoming heated, a thermally operable switch responsive to conditions caused by operation of the main burner, and means controlled by said thermally operable switch for shunting the first said resistance element in the initial position of said controlling means.

7. A control system for fuel burners having main and pilot burners comprising in combination, a source of electrical energy, electrically operable means connected to said source for controlling the supply of fuel to the main burner, said means having an initial position preventing fuel supply to the main burner and being actuatable to another position when current of sufficient value is supplied thereto, a resistance element in circuit with said controlling means and being adapted to vary in resistance in response to variations in current values in said circuit, a second resistance element shunting said controlling means and being located to be heated by the pilot burner, said second resistance element being adapted to vary in resistance in response to thermal variations therein caused by the heat of the pilot burner, switching means having a timing element for short-circuiting said controlling means while said second resistance is becoming heated, a third resistance element, and a thermally operable switch responsive to conditions caused by operation of the main burner and operable with said third resistance for shunting the first said resistance in the initial position of said controlling means, said thermal switch being

operable in said other position of said controlling means for discontinuing said first resistance shunt during operation of the main burner.

8. A control system for fuel burners having main and pilot burners comprising in combination, a source of electrical energy, electrically operable means connected to said source for controlling the supply of fuel to the main burner, said means having an initial position preventing fuel supply to the main burner and being actuatable to another position when sufficient current is supplied thereto, a resistance element in series circuit with said controlling means and being capable of increasing substantially in its resistance upon passage of current therethrough, a second resistance element shunting said controlling means and being capable of increasing substantially in its resistance as its temperature increases, said second resistance being exposed to the heat of the pilot burner, switching means having a timing element for short-circuiting said controlling means while said second resistance is becoming heated, a third resistance element having fixed impedance value, and a thermally operable switch responsive to conditions caused by operation of the main burner and cooperable with said third resistance for shunting the first said resistance in the initial position of said controlling means, said thermal switch being operable in said other position of said controlling means for discontinuing said first resistance shunt during operation of the main burner.

9. A combined ignition and control system for fuel burners having main and pilot burners, comprising a source of electrical energy, electrically operable means connected to said source for controlling fuel supply to the main burner, said controlling means having an initial position in which said fuel supply is prevented and being actuatable to another position where fuel supply is permitted, switching means having a timing element short-circuiting said controlling means and causing it to remain in said initial position for a predetermined period, igniting means for the pilot burner having separate connection with said source, second switching means having a timing element for electrically disconnecting said igniting means after a predetermined period independent of that of the first said timing element, a resistance element in circuit with said controlling means and being adapted to vary in resistance in response to variations in current

values in the said circuit thereof, a second resistance element shunting said controlling means and being located to be heated by the pilot burner, said second resistance element being adapted to vary in resistance in response to thermal variations therein caused by the heat of the pilot burner, and a thermally operable switch responsive to conditions caused by operation of the main burner and being operable for shunting the first said resistance element in the initial position of said controlling means.

10. A combined ignition and control system for fuel burners having main and pilot burners, comprising a source of electrical energy, electrically operable means connected to said source for controlling the fuel supply to the main burner, said controlling means having an initial position where said fuel supply is prevented and being actuatable to another position in which fuel supply is permitted, switching means having a timing element short-circuiting said controlling means and causing it to remain in said initial position for a predetermined period, igniting means for the pilot burner having separate connection with said source, second switching means having a timing element for electrically disconnecting said igniting means after a predetermined period less than that of the first said timing element, electromagnetic means energized from said source and common to both said switching means for operating the same simultaneously to initiate said timing periods, a resistance element in circuit with said controlling means and being capable of increasing substantially in its resistance upon passage of current therethrough, a second resistance element shunting said controlling means and being capable of increasing substantially in its resistance as its temperature increases, said second resistance element being exposed to the heat of the pilot burner, a third resistance element, and a thermally operable switch responsive to conditions caused by operation of the main burner and cooperable with said third resistance for shunting the first said resistance in the initial position of said controlling means, said thermal switch being operable in said other position of said controlling means for discontinuing said first resistance shunt during operation of the main burner.
